CLAIM

The ornamental design for a midsole periphery as shown and described.

DESCRIPTION

FIG. 1 is a perspective view of the midsole periphery in accordance with my new design;
FIG. 2 is a right side view thereof;
FIG. 3 is a left side view thereof;
FIG. 4 is a front view thereof;
FIG. 5 is a rear view thereof;
FIG. 6 is a top view thereof; and,
FIG. 7 is a bottom view thereof.

The dash-dash broken lines shown in the drawings represent environmental structure showing parts of the upper and outsole bottom as well as portions of the midsole periphery that form no part of the claimed design. The dot-dashed broken lines define the bounds of the claimed design and form no part thereof.
